UNITED STATES PATENT OFFICE.

ANGELO C. HARPER, OF WASHINGTON, DISTRICT OF COLUMBIA.

SAFETY ATTACHMENT FOR AEROPLANES.

Application filed August 26, 1927. Serial No. 215,673.

This invention relates to a safety attachment for aeroplanes and has for its object to provide, in a manner as hereinafter set forth, to retard the fall of the aeroplane in a manner to insure for a safe landing thereof in the event of the inactivity of the driving means for the aeroplane, or when the motor, propeller or wings become damaged.

A further object of the invention is to provide, in a manner as hereinafter set forth, a safety attachment for aeroplanes under convenient control of the aviator and for suspension from the bottom of the fuselage, driven from the interior of the latter, independent of the driving motor of the aeroplane, for retarding the descent of the latter, in case of accident to the driving and sustaining means of the vessel, thereby providing for a safe landing and non-injury to the vessel, as well as to the occupant or occupants thereof.

Further objects of the invention are to provide, in a manner as hereinafter set forth, a safety attachment for aeroplanes, which is comparatively simple in its construction and arrangement, strong, durable, compact, adjustable, operated independently of the driving means for the aeroplane, thoroughly efficient in its use, preventing a too rapid descent of the vessel when its driving or sustaining means becomes inactive, readily installed in position without necessitating a change in structure of the vessel with which it is to be attached, and comparatively inexpensive to set up.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a fragmentary view in side elevation, of an aeroplane showing the adaptation therewith of an attachment therefor in accordance with this invention.

Figure 2 is a front elevation, partly in section of the safety attachment.

Figure 3 is a fragmentary view, in plan, of the safety attachment.

Figure 4 is a section on line 4—4 Figure 2.

Figure 5 is a modified form of the transmission shaft, broken away.

Referring to the drawings in detail 1 denotes a fuselage of an aeroplane, 2 a wing and 3 a propeller driven by a suitable motor not shown, 4 the landing gear and 5 the bottom of the fuselage 1, and said bottom is provided at one side with a longitudinally extending slot 6 and an opening 7 arranged rearwardly of the slot 6. The landing gear 4 is arranged forwardly of the slot 6. The foregoing elements are of known construction, with the exception of providing the bottom 5 of the fuselage 1 with the slot 6 and opening 7, and said elements are illustrated so that the adaptation of a safety attachment, in accordance with this invention, can be illustrated in operative relation with respect to the vessel.

The safety attachment, in accordance with this invention, includes a pair of spaced hangers 8, 9 each having its lower end formed with a bearing 10. The hangers are secured against the lower face of the bottom 5, by the holdfast devices 11 and said hangers are positioned at each side of said bottom 5 and a substantial distance forwardly with respect to the landing gear 4. Positioned between the bearings 10 a substantial distance below the bottom 5 of the fuselage 1, is a tiltable bar 12, provided at each end with a trunnion 13, which extends through and is mounted in a bearing 10. Each end of the bar 12 inwardly with respect to a trunnion 13 is provided with a depending socket forming member 14 which constitutes a bearing. The members 14 are disposed at right angles with respect to the ends of the bar 12.

Arranged below and spaced a substantial distance from the bar 12 is a support 15 provided at each end with an upstanding, right angularly disposed socket forming member 16 which constitutes a bearing, and said members 16 are arranged in alignment with the members 14. The support 15, in proximity to or spaced an appropriate distance from a member 16, is formed with a vertically dis-

posed arm 17 of less height than the height of the member 16 and provided at its upper end with a bearing 18. Interposed between the bar 12 and support 15 is a pair of spaced 5 suspension bars 19, 20 and which also provide combined connecting and bracing members. The bars 19, 20 are secured at their upper ends, as at 21 to the bar 12 and at their lower ends are secured, as at 22 to the support 15. 10 The suspension bars, in the proximity to their lower ends are formed with openings 23 for a purpose to be presently referred to. The bars 19, 20 are spaced an appropriate distance from the socket forming members 14, 16. 15 The bar 12, support 15 and bars 19, 20 provide a supporting structure for a pair of rotatable retarding elements which are horizontally disposed and as said elements are of like construction, but one will be described, as 20 the description of one will apply to the other. The function of the retarding elements is to prevent a too rapid descent or fall of the vessel in case that its propelling means become inactive or the wings are injured, and by providing means to prevent a too rapid descent 25 or fall of the vessel it culminates in a safe landing and prevents injury to the vessel as well as to the occupant or occupants thereof.

Each sustaining element comprises a vertically disposed hub 24 having a reduced upper end 25 and a reduced lower end 26 and with the reduced lower end 26 of greater length than the reduced upper end 25. The forming of the hubs 24 with the reduced ends 30 provide shoulders 27, 28. The hub 24, centrally thereof, is formed with a laterally extending annular flange 29 and connected therewith is a series of radially extending blades 30 having curved outer ends 31. The 35 blades 30 are disposed at an inclination with respect to the longitudinal axis of the hub 24. Mounted against the top and bottom edges of the blades, as well as being secured therewith, are flat holding rings 32 of appropriate outer diameter and with the inner diameter thereof of slightly greater than the outer diameter of the flange 29. The rings 32 in connection with the holdfast means 33 for securing the blades to the flange 29, prevent any twist or shift 40 of the blades relatively to each other and maintain the blades in uniform spaced relation. The upper ends 25 of the hubs 24 extend into the socket forming members 14 and the shoulders 27 of the hubs 24 abut against the lower ends of said members 14. The 45 reduced lower ends 26 of the hubs 24 extend into the members 16. Fixedly secured to each reduced lower end 26 by a holdfast device 34 is the hub 35 of a bevel pinion 36 having the lower portion of its hub bearing against the upper end of a member 16. The upper end of the hub 35 abuts against a shoulder 28. The bevel pinions 36 are driven, by a means to be presently referred to, to provide for the operation 50 of the retarding elements. Mounted in

the bearings 18 and extending through the openings 23 in the bars 19, 20 is a transmission shaft 37, provided at each end with a bevel gear 38 meshing with a bevel gear 36, and on the operation of one of the bevel pinions 36 the other will be simultaneously operated due to the operative drive connection provided by the shaft 37 and the pair of bevel pinions 38.

The attachment includes an operating shaft 75 and as illustrated in Figures 1, 3 and 4 said shaft comprises an end section 39, an end section 40 having a portion of its length flexible, an intermediate section 41 having one end thereof enlarged as at 42, and formed 80 with a socket as at 43, and further formed with a peripheral groove 44. The end section 40 is connected to the socketed portion 42 of the intermediate section 41. The end section 39 is connected to the intermediate section 41 by a universal joint 45. One end of the support 15 is provided with a rearwardly extending bracket or arm 46 which provides a bearing for the shaft section 39, and the latter is provided with a bevel pinion 47, 90 which meshes with one of the bevel pinions 36 for driving the retarding elements. Secured to the bottom 5 of the fuselage 1 is a bracket 48 arranged in alignment with that end of the support 15 which is formed by 95 the arm 46. The shaft section 40 is journaled in the lower end of the bracket 48 and carries a bevel pinion 49. Arranged within the fuselage 1 and independent of the driving motor of the vessel, is a motor 50 employed for driving a vertically disposed shaft 51 which extends down through the opening 7, is guided by the bracket 48, as well as supported thereby and carries on its lower end a bevel pinion 52 which meshes with the bevel pinion 49. The upper end of the shaft 51 carries a bevel pinion 53 which meshes with a bevel pinion 54 formed on the end of the shaft of the motor 50. The motor is to be in convenient reach of the aviator, so that it can be thrown 100 into operation to drive the retarding elements, when it is discovered that the driving and sustaining means of the vessel are not functioning in a proper manner.

The supporting structure for the retarding elements can be tilted forwardly and rearwardly and for such purpose there is arranged within the fuselage 1 a shifting lever 55, having associated therewith a latching mechanism 56 therefor of known construction. 115 The lever 55 extends down through the slot 6 and is coupled to the socketed portion 42 of the shaft section 41. The lower end of the lever 55 is formed with oppositely disposed pins 57 which operate in the groove 44. By this arrangement the lever is connected with the operating shaft, so that when the lever is shifted in one direction the flexible shaft section 40 will give to a certain extent and the operating shaft will bend in a manner 120 125 130

at the universal joint 45, see dotted line position in Figure 1, and the supporting structure for the retarding elements will be tilted rearwardly. When the supporting structure is tilted forwardly the shaft sections 39, 40 and 41 will assume a position reverse to that shown by dotted lines in Figure 1. The connection between the lever 55 and operating shaft is such as not to interfere with the rotation of the latter.

The modified form of operating or transmission shaft shown in Figure 5 comprises an intermediate section 58 and a pair of end sections 59, 60, and the former is connected 15 to the section 58 by a universal joint 61 and the section 60 is connected to the section 58 by a universal joint connection 62. The section 59 is provided with a bevel gear 63 and the section 60 with a bevel gear 64. The 20 section 58 is provided intermediate its ends with an enlarged peripherally grooved portion 65 for connecting therewith the lower end of the shifting lever 55.

Connected to the bars 19, 20 and arranged 25 in spaced relation with respect to the retarding elements are oppositely disposed, rearwardly extending, windshields 65, 66 of arcuate shape and they function to deflect the air current created by the retarders, in a 30 manner whereby the air currents created by one retarder will be deflected away from the other thereby functioning as deflectors.

The retarders rotate in opposite directions with respect to each other and one travels 35 in the direction of the arrow 67 and the other in the direction of the arrow 68. The retarders are so mounted as to have a portion project laterally from each side of the fuselage, and when active function in a manner 40 to retard the descent or fall of the vessel in case there is something wrong with the propelling and retaining means thereof. The retarders are rotated from the motor 50 at a speed to provide for efficiently performing the 45 function for which the retarders are intended. The retarders are not driven from the driving motor of the vessel, but from an independent motor capable of being quickly thrown into operation by the aviator when occasion requires. The latching means which 50 associates with the shifting lever 55 will maintain the latter in set position so as to hold the supporting structure for the retarders in its adjusted position as oftentimes as it is advisable to dispose the retarders at an upward or a downward inclination.

It is thought the many advantages of a safety attachment for aeroplanes, in accordance with this invention, can be readily understood, and although the preferred embodiment of the invention is as illustrated and described, yet it is to be understood that changes in the details of construction can be had which will fall within the scope of the invention as 55 claimed.

What I claim is:

1. A safety attachment for aeroplanes comprising a pair of horizontally disposed retarding elements for operation in opposite directions, means for suspending said elements from the bottom of the fuselage of the aeroplane, a motor positioned within the fuselage and independent of the driving means for the aeroplane, an operative drive connection for and leading from said motor to said elements, and vertically disposed deflectors carried by said suspension means and located between said elements.

2. A safety attachment for aeroplanes comprising a pair of horizontally disposed retarding elements for operation in opposite directions, means for suspending said elements from the bottom of the fuselage of the aeroplane, a motor positioned within the fuselage and independent of the driving means for the aeroplane, an operative drive connection for and leading from said motor to said elements, means for simultaneously tilting said retarding elements, and oppositely disposed deflectors carried by said suspension means and associated with said elements.

3. A safety attachment for aeroplanes comprising a pair of horizontally disposed retarding elements for rotation in opposite directions, means for suspending said elements from the bottom of the fuselage of the aeroplane forwardly of the landing carriage of the latter, a motor positioned within the fuselage rearwardly of the landing carriage 95 of the aeroplane and independent of the driving means for the latter, an operative drive connection leading to said elements from said motor, and means attached to said operative drive connection for tilting said 100 elements in opposite directions with respect to the bottom of the fuselage.

4. A safety attachment for aeroplanes comprising a pair of horizontally disposed retarding elements for rotation in opposite directions, means for suspending said elements from the bottom of the fuselage of the aeroplane forwardly of the landing carriage of the latter, a motor positioned within the fuselage rearwardly of the landing carriage 110 of the aeroplane and independent of the driving means for the latter, an operative drive connection leading to said elements from said motor, and a pair of oppositely disposed, rearwardly extending deflectors 115 carried by said suspension means and associated with said elements to prevent the air current created by one passing to the other.

5. A safety attachment for aeroplanes comprising a pair of horizontally disposed retarding elements for rotation in opposite directions, means for suspending said elements from the bottom of the fuselage of the aeroplane forwardly of the landing carriage of the latter, a motor positioned within the 125 130

fuselage rearwardly of the landing carriage of the aeroplane and independent of the driving means for the latter, an operative drive connection leading to said elements from 5 said motor, means attached to said operative drive connection for tilting said elements in opposite directions with respect to the bottom of the fuselage, and a pair of oppositely

disposed, rearwardly extending deflectors 10 carried by said suspension means and associated with said elements to prevent the air current created by one passing to the other.

In testimony whereof, I affix my signature hereto.

ANGELO C. HARPER.
